(57) CLAIM

I claim the ornamental design for a handbag, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a front perspective view of a handbag according to my design;

FIG. 2 is a front elevation view of the handbag of FIG. 1;

FIG. 3 is a rear elevation view of the handbag of FIG. 1;

FIG. 4 is a right side elevation view of the handbag of FIG. 1;

FIG. 5 is a left side elevation view of the handbag of FIG. 1;

FIG. 6 is a top plan view of the handbag of FIG. 1; and,

FIG. 7 is a bottom plan view of the handbag of FIG. 1.

The broken lines showing a portion of the handbag are for the purposes of illustrating environment and form no part of the claimed design.
